UNITED STATES PATENT OFFICE.

EDWIN L. RUSSELL, OF CLEVELAND, OHIO.

VALVE ADJUSTER AND DRIVER.

1,153,710.

Specification of Letters Patent. Patented Sept. 14, 1915.

Application filed March 16, 1912, Serial No. 684,313. Renewed February 8, 1915. Serial No. 6,806.

To all whom it may concern:

Be it known that I, EDWIN L. RUSSELL, a citizen of the United States, residing at Cleveland, in the county of Cuyahoga and 5 State of Ohio, have invented a new and useful Valve Adjuster and Driver, of which the following is a specification.

The object of my invention is to provide a simple connection between a valve or other 10 seated member and its driving member, by means of which, upon undue resistance of the valve to movement along its seat, the valve will be given automatically a sufficient initial movement from its seat to be relieved 15 therefrom.

The accompanying drawings illustrate my invention.

Figure 1 is an axial section, embodying my invention; Fig. 2 is an axial fragmentary section on line 2-2 of Fig. 1, and 20 Fig. 3 a section on line 3-3 of Fig. 2.

In the drawings, 10 indicates an axially tapered rotary valve seated in a correspondingly tapered casing or seat 11. The rotary 25 driving shaft 12 is held against axial movement by any suitable means such as flanges 13 and casing 14. The free end of shaft is reduced at 15 and journaled upon this reduced end is a sleeve 16 having an external 30 thread 17 which is conveniently a square thread. The external diameter of threads 17 is such that the sleeve 16 fits within the pocket 18 formed in the adjacent end of valve 10 and the sleeve 16 is prevented from 35 relative rotation within the pocket by means of a spline 19, engaging said sleeve 16. One end of sleeve 16 rests upon a shoulder 21 on shaft 12 and the axial length of sleeve 16 is sufficient to fill the pocket 18. Mount- 40 ed between the threads 17 is a spring helix 22 having an internal diameter somewhat greater than the diameter of sleeve 16 at the base of the threads and an internal diameter less than the internal diameter of 45 the pocket. One end of this helix is connected at 23 to shaft 12 while the other end

is connected at 24 to valve 10. The thread 17 is cut away at 25 so that the adjacent end of the helix 22 may have freedom of angular movement relative to the sleeve 16. 50

If the shaft 12 be rotated in the direction indicated by the arrow and there be no abnormal resistance to movement of the valve 10 within its seat, the driving connection between the shaft and valve will serve to 55 drive the valve rotatively. If there be abnormal resistance to movement of the valve the shaft end of the helix 22 will be moved angularly relative to the threads 17 and, as the sleeve 16 is held against rotation by the 60 resistance of valve 10, there will be a cam movement of the helix upon the thread thus projecting the sleeve 16 axially relative to shaft 12 and driving valve 10 away from its seat enough to relieve the abnormal resist- 65 ance. If shaft 12 be rotated in the opposite direction and there be abnormal resistance to movement of the valve, the helix will rotate within the space between the threads and will thus be driven axially relative to 70 the shaft and thus will shift the valve 10 away from its seat enough to relieve the abnormal resistance.

I claim as my invention:

The combination of a seat member, a rotary seated member mounted thereon, a threaded member splined to the seated member and substantially coaxial therewith, a driving shaft, and a spring helix mounted between the threads of the threaded member 80 and anchored at one end to the driving shaft and anchored at the other end to the rotary seated member.

In witness whereof, I have hereunto set my hand and seal at Indianapolis, Indiana, 85 this ninth day of March, A. D. one thousand nine hundred and twelve.

EDWIN L. RUSSELL. [L. s.]
